CLAIM

The ornamental design for a connector housing, as shown and described.

DESCRIPTION

FIG. 1 is a front, top, and side perspective view of a connector housing showing our new design;

FIG. 2 is a rear, bottom, and opposite side perspective view thereof;

FIG. 3 is a front perspective thereof, shown without the locking spring for clarity of illustration only; and,

FIG. 4 is a rear perspective view of FIG. 3.
